US0D1065173S

(12) **United States Design Patent** (10) **Patent No.:** **US D1,065,173 S**
(45) **Date of Patent:** **** Mar. 4, 2025**

(54) **COMPUTER**

(71) Applicant: **IQM Finland Oy**, Espoo (FI)

(72) Inventors: **Lauri Lumme**, Oulu (FI); **Viljami Räisänen**, Espoo (FI); **Matti Juhani Ruohonen**, Espoo (FI)

(73) Assignee: **IQM Finland Oy**, Espoo (FI)

(**) Term: **15 Years**

(21) Appl. No.: **29/891,847**

(22) Filed: **May 10, 2023**

(30) **Foreign Application Priority Data**

Nov. 10, 2022 (EM) 015002865-0001

(51) **LOC (15) Cl.** **14-02**

(52) **U.S. Cl.** **D14/300**
USPC .....

(57) **CLAIM**

The ornamental design for a computer as shown and described.

DESCRIPTION

FIG. 1 is a front perspective view of a computer showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The figures show contrast in appearance and do not claim the color black.

1 Claim, 8 Drawing Sheets
